United States Patent Office

Des. 175,928
Patented Nov. 1, 1955

175,928

DOOR CLOSER CASING

Benjamin S. Bernhard, New Britain, Conn., assignor to
The American Hardware Corporation, New Britain,
Conn., a corporation of Connecticut

Application November 17, 1954, Serial No. 33,139

Term of patent 14 years

(Cl. D10—7)

Fig. 1.

Fig. 5.

Fig. 2.

Fig. 3.

Fig. 4.

Fig. 1 is a plan view of a door closer casing embodying my new design.

Fig. 2 is an end view thereof; the opposite end of said casing being the same as that illustrated.

Fig. 3 is a front view of said casing.

Fig. 4 is a rear view thereof.

Fig. 5 is a bottom view thereof.

I claim:

The ornamental design for a door closer casing, as shown and described.
